UNITED STATES PATENT OFFICE.

GEORGE WILLIAM DAVIS, OF GRANVILLE, NEW YORK.

THILL-COUPLING.

SPECIFICATION forming part of Letters Patent No. 632,550, dated September 5, 1899.

Application filed February 27, 1899. Serial No. 706,997. (No model.)

To all whom it may concern:

Be it known that I, GEORGE WILLIAM DAVIS, of Granville, in the county of Washington and State of New York, have invented a new and Improved Thill-Coupling, of which the following is a full, clear, and exact description.

The object of my invention is to so construct a thill-coupling that when the draft-animal is removed from the thills the thills will be automatically carried upward to a position of rest and held in such position.

Another object of the invention is to so construct a thill-coupling that the thills or shafts may be quickly and conveniently disconnected from a vehicle or applied thereto and when applied to the vehicle will remain in operative position under all conditions of travel and be practically noiseless while utilized for draft purposes.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a vertical section through the axle of a vehicle and a side elevation of the improved thill-coupling, the thills shown in positive lines and partly in section being in the position to be entered upon the coupling, the dotted lines illustrating the position of the thill after having been entered upon the coupling. Fig. 2 is a view similar to Fig. 1, illustrating in dotted lines the position the thills will occupy after the animal has been disconnected therefrom, the position shown in positive lines being that which the thills will occupy when the draft-animal is harnessed thereto. Fig. 3 is a plan view of a portion of the axle and the improved coupling, the thills having been removed; and Fig. 4 is a detail rear elevation of the lower end of a thill adapted for use in connection with the coupling.

A represents the front axle of a vehicle, and B the clip that is adapted to secure the improved coupling to the axle. The clip E is made to pass through a horizontal plate 10, forming a part of the body of the coupling,

which plate extends below the axle and beyond the front and the rear thereof, and said plate is provided at each side of its forward end with an ear 11.

The movable portion of the coupling consists of a sleeve or barrel 12, located between the ears 11 of the body portion of the coupling and mounted to turn upon a screw or pin 13, passed through the barrel or sleeve 12 and through the ears 11, one end of said screw or pin being provided with a head and the other end with a nut 14 or the equivalent thereof. A projection 15 is formed at the forward portion of the barrel or sleeve 12, and said projection while extending forwardly likewise extends downwardly a distance below said sleeve or barrel. The projection 15 is provided in its upper surface with a recess 16, 70 the forward portion of the barrel 12 constituting one wall of said recess. The front or forward portion of the projection 15 is formed upon the lines of a compound curve, whereby a nose 17 is produced at the lower end of said projection, and from said nose 17 an arm 18 is rearwardly projected, said arm being more or less downwardly and rearwardly curved. The upper surface of the arm 18 is adapted to engage with a member of a bent spring 19, 80 said spring being secured, preferably, between the axle A and body-plate 10 of the coupling, the lower end of the spring being curved in direction of one side of the running-gear, extending transversely over the upper 85 surface of the arm 18, as shown in Figs. 1 and 2.

Each thill or shaft C is provided with a shoe D at its rear end, and an opening 20 is produced in said shoe, which opening at its bottom 21 has a downward and rearward inclination.

When the improved couplings are employed and the thills or shafts are connected with the couplings, said thills or shafts are carried to 95 the position shown in dotted lines in Fig. 1, the upper walls of the openings 20 in the shoes of the thills or shafts entering the recesses 16 in the projection of the movable portions of said couplings. By pressing upward the arms 18 of the couplings, as shown in dotted lines in Fig. 1, the spring 19 is compressed, and the noses 17 of the couplings are brought in such position that the lower portion of the open-

ings 20 in the thills may be carried over the said noses, as shown in dotted lines in Fig. 1. The thills will thus be securely fastened to the couplings, and when the vehicle is not in use the springs 19 by forcing downward the arms 18 will carry the thills to the position shown in dotted lines in Fig. 2 and hold the thills in such position, so that wherever the vehicle may be the thills will be held at an elevation from the ground or other support for said vehicle. When an animal is to be harnessed to the vehicle, the thills are drawn downward, assuming the position shown in positive lines in Fig. 2, wherein it will be observed that the thills are in firm engagement with the couplings and that the springs 19 are compressed, and it is evident also that under the improved construction of the coupling the thills when coupled thereto will not rattle or have undue wear while the vehicle is in use.

Having thus described my invention, I claim as new and desire to secure by Letters Patent—

1. A thill-coupling, consisting of a body-section adapted for attachment to an axle, a locking-section pivotally attached to the body-section, said locking-section being provided with means for attachment to a thill and with an arm extending rearwardly beyond and beneath the body-section, and a spring attached to a fixed support, which spring extends over the upper surface of the projecting arm of the locking-section, as described.
2. A thill-coupling, consisting of a body-section provided with means for attachment to the running-gear, and a locking-section pivotally attached to the body-section, said locking-section being provided with an upper recess, a lower nose and an arm extending rearwardly from said nose, and a spring adapted for attachment to the running-gear, which spring extends across the upper surface of said arm, for the purpose described.
3. In a thill-coupling, the combination with a body-section comprising a bottom or base plate adapted for attachment to the running-gear of a vehicle, and ears projected upwardly

from the forward portion of said base-plate, of a locking-section comprising a barrel located between said ears of the body-section, a pivot-pin passed through the ears of the body-section and through the barrel of the locking-section, the locking-section being provided with an extension at the forward portion of the barrel, projecting downwardly below the barrel, which extension has a recess formed in its upper surface, a forwardly-extending nose at its lower end, and a rearwardly-extending arm at its bottom portion, and a spring adapted for attachment to the running-gear, which spring is in engagement with the upper surface of the arm of the locking-section of the coupling, as described.

4. In a thill-coupling, the combination, with a body-section comprising a bottom or base plate adapted for attachment to the running-gear of a vehicle, and ears projected upwardly from the forward portion of said base-plate, of a locking-section comprising a barrel located between said ears of the body-section, a pivot-pin passed through the ears of the body-section and through the barrel of the locking-section, the locking-section being provided with an extension at the forward portion of the barrel, projecting downwardly below the barrel, which extension has a recess formed in its upper surface, a forwardly-extending nose at its lower end, and a rearwardly-extending arm at its bottom portion, a spring adapted for attachment to the running-gear, which spring is in engagement with the upper surface of the arm of the locking-section of the coupling, and a thill provided with a foot having an opening therein, the bottom wall of the opening being inclined, the upper wall of said opening of the thill-foot being adapted to engage with the lower wall of the recess in the locking-section of the coupling, the lower wall of said opening in the thill-foot being adapted to engage with the nose on said locking-section of the coupling, as described.

GEORGE WILLIAM DAVIS.
